UNITED STATES PATENT OFFICE

PHILIP E. WILLMAN, OF CHICAGO, ILLINOIS

DESIGN FOR AN ASH TRAY OR SIMILAR ARTICLE

Application filed January 27, 1933. Serial No. 47,009. Term of patent 7 years.

To all whom it may concern:

Be it known that I, PHILIP E. WILLMAN, a citizen of the United States, residing at Chicago, in the county of Cook and State of Illinois, have invented a new, original, and ornamental design for an Ash Tray or Similar Article, of which the following is a specification, reference being had to the accompanying drawing, forming part thereof.

Figure 1 is a view in perspective of an ash tray or similar article embodying my new design, and

I claim:—

The ornamental design for an ash tray or similar article substantially as shown.

PHILIP E. WILLMAN.
